UNITED STATES PATENT OFFICE.

EZRA DIXON, OF BRISTOL, RHODE ISLAND.

TOP-ROLL SADDLE.

No. 912,650.

Specification of Letters Patent.

Patented Feb. 16, 1909.

Application filed April 12, 1906. Serial No. 311,330.

To all whom it may concern:

Be it known that I, EZRA DIXON, a citizen of the United States, residing at Bristol, in the county of Bristol and State of Rhode Island, have invented a new and useful Improvement in Top - Roll Saddles, of which the following is a specification.

This invention has reference to an improvement in top roll saddles and more particularly to an improvement in the construction of the front top roll saddle and the weight stirrup.

In top roll saddles where notches are used in the front saddle to hold the upper end of the weight stirrup in the adjusted position, the weight stirrup through the vibration of the machine or other causes is liable to jar out of the notches and become misplaced, thus ruining the fine adjustment of the weight stirrup on the saddle required in certain counts of yarn.

The object of my invention is to improve the construction of top roll saddles whereby the weight stirrup is adjustable on the front saddle and locked in the adjusted position.

My invention consists in the peculiar and novel construction of the front top roll saddle and the upper end of the weight stirrup, as will be more fully set forth hereinafter and pointed out in the claims.

Figure 1 is a side view of the top roll saddles, showing the weight stirrup locked to the front saddle and the saddles in their operative position on the journals of the top rolls. Fig. 2 is a transverse sectional view through the front saddle, showing the catch on the upper end of the weight stirrup in the locked position. Fig. 3 is a transverse sectional view through the front saddle. Fig. 4 is a face view of the upper end of the weight stirrup, showing the catch in the unlocked position, and Fig. 5 is a face view of the upper end of a weight stirrup, showing the modified form of catch.

In the drawings, *a* indicate the top roll journals, *b* the back saddle, *c* the front saddle, and *d* the weight stirrup. The back saddle *b* has the usual bearings *6* for the back and intermediate top roll journals. The front saddle *c* has the bearing *7* for the front top roll journal and the row of up-

wardly-extending projections *8* forming the deep notches *9* on the top of the saddle, as shown in Figs. 1 and 3. The weight stirrup *d* has the square opening *10* in the upper edge of which is the nick *11* for the projections *8* and the catch *12* pivotally secured to the end of the weight stirrup by the rivet *13* in a position for the short end *14* of the catch to cover or uncover the nick *11*, as shown in Figs. 2 and 4, otherwise the front saddle and the weight stirrup may have the usual construction of front saddles and weight stirrups.

The weight stirrup *d* is adjusted on the front saddle by moving the weight stirrup over the saddle lengthwise, the saddle passing through the opening *10* and the projections *8* through the nick *11* in the weight stirrup and secured in the adjusted position by turning the catch *12* so as to bring the short end *14* of the catch into a notch *9* in the top of the saddle and cover up the nick *11* in the weight stirrup, as shown in Figs. 1 and 2. In the regular form, as shown in Figs. 2 and 4, the stirrup is locked to the saddle in a notch *9* by raising the long arm *15* of the catch *12* into a vertical position and in the modified form, as shown in Fig. 5, the stirrup is locked to the saddle by depressing the long arm of the catch *12* into a horizontal position, as shown in broken lines.

Having thus described my invention, I claim as new and desire to secure by Letters Patent:—

1. A weight stirrup *d* having a square opening *10* in the upper edge of which is a nick *11*, a catch *12* having the short arm *14* and the long arm *15* and pivotally secured to the weight stirrup by a rivet *13* in a position for the short arm *14* to cover or uncover the notch *11*, as described.

2. The combination of a front top roll saddle *c* having a row of upwardly-extending projections *8* forming a series of deep notches *9* on the top of the saddle and a weight stirrup *d* having a square opening *10* for the saddle *c* and in the upper edge of which is a nick *11* for the projections *8* on the saddle, and a catch *12* having the short arm *14* and the long arm *15* and pivotally

secured to the weight stirrup by a rivet 13 in a position for the short arm 14 to cover or uncover the nick 11, whereby the weight stirrup *d* is adjustable on the saddle *c* and 5 locked in the adjusted position to the saddle, as described.

In testimony whereof I have signed my

name to this specification in the presence of two subscribing witnesses.

EZRA DIXON.

Witnesses:

ADA E. HAGERTY,
J. A. MILLER.
